(57) **CLAIM**

The ornamental design for a refrigeration apparatus, as shown and described.

DESCRIPTION

FIG. 1 is a perspective view of a refrigeration apparatus according to my new design;

FIG. 2 is a top plan view thereof;

FIG. 3 is a front elevational view thereof;

FIG. 4 is a left side elevational view thereof;

FIG. 5 is a rear elevational view thereof; and,

FIG. 6 is a bottom plan view thereof.

FIGS. 2 through 6 are shown on an enlarged scale.

The broken lines shown in the drawing disclosure are for illustrative purposes only and form no part of the claimed design.
